UNITED STATES PATENT OFFICE.

CHARLES F. PYM, OF DETROIT, MICHIGAN, ASSIGNOR, BY MESNE ASSIGNMENTS, TO
UNITED SHOE MACHINERY CORPORATION, OF PATERSON, NEW JERSEY, A COR-
PORATION OF NEW JERSEY.

PROCESS OF LASTING BOOTS OR SHOES.

1,412,892.

Specification of Letters Patent. Patented Apr. 18, 1922.

Application filed May 9, 1913, Serial No. 766,471. Renewed August 29, 1916. Serial No. 117,561.

To all whom it may concern:

Be it known that I, CHARLES F. PYM, a subject of the King of England, residing at Detroit, in the county of Wayne and State 5 of Michigan, have invented certain new and useful Improvements in Processes of Lasting Boots or Shoes, of which the following is a specification, reference being had therein to the accompanying drawings.

10 This invention relates to the art of making boots and shoes, and more particularly to that portion of the processes of manufacture known as lasting in which a boot or shoe upper upon a last is stretched or formed 15 closely to the last and into position to be secured to a sole upon the last.

General objects of the invention are so to improve methods of shoe manufacture as to utilize skilled and relatively unskilled labor 20 to the best advantage in the different operations; to enable certain operations to be performed with less hand labor than is now employed, or by more or less automatic machinery; and to improve the conformation to 25 its last of portions of the upper that are visible in the completed shoe, particularly portions at and adjacent to the edge of the shoe bottom.

In one of its aspects the invention aims to 30 accomplish the desired results by assembling an upper on a last, manipulating the upper into conformity with the contour of the last around the toe below the bottom of the shoe (assuming the shoe to be sole face 35 upward and using the term "sole" generically to include an innersole) and applying a binder around the toe below the bottom of the shoe and securing the binder. This operation, which involves shaping the most 40 conspicuous and the most difficult portion of a shoe, can advantageously be performed by or under the supervision of skilled labor and, in accordance with further inventions of mine, by the aid of more or less automatic 45 machinery. Under suitable conditions the binder can be made to effect a molding of the upper at and near the edge of the shoe bottom continuing during the interval between the toe lasting and a subsequent upper and 50 sole connecting operation. The binder also presents a guiding surface for engagement with the machine edge rest during the subsequent upper and sole connecting operation

and holds the upper from being pushed ahead longitudinally of the shoe edge by the 55 edge rest as the connecting operation is carried on progressively around the toe.

In another of its aspects the invention contemplates engaging the marginal edge of an upper and stretching the upper into substantial conformity with the contour of a contained last or form around the toe below the edge of the last bottom, gathering the tensioned upper smoothly to the last substantially at the edge of the last and holding the 65 upper against slipping back by a flexible binder applied exteriorly of the shoe bottom and then releasing the edge of the upper, and subsequently securing the upper to a sole 70 and then removing the binder. The operation under consideration deals with the forepart of the upper, and a forepart form, as distinguished from a full length last, may be used and the upper stretched thereover and then gathered around and bound against the 75 exterior faces of the form by the flexible binder which leaves the margin of the upper at and above the sole line free for manipulation in a subsequent upper and sole connecting operation. 80

In a further aspect of this invention in the manufacture of certain classes of shoes, it contemplates including, at a convenient time subsequent to the binding, an additional step of forming the free upstanding margin of 85 the upper inwardly and down upon the bottom face of the sole by an inward wiping operation over the upper edge of the binder by which the upper is held in conformity with the contour of the side faces of the toe portion 90 of the last. This step may or may not be associated with a concurrent upper and sole connecting operation.

The invention will be more fully understood from the following description and accompanying drawings which fully explain 95 how it may be practised, and the invention will then be more particularly pointed out in the claims. In said drawings, the invention has been illustrated in Figs. 1 and 2 as 100 applicable to the manufacture of any class of shoe and in Fig. 3 is shown a contemplated carrying forward of the invention to include a subsequent step of forming the free upstanding margin of the upper of the shoe 105 shown in Fig. 2 down upon the sole and a

concurrent appropriate securing of the upper to the sole in the manufacture of a particular class of shoes, namely, McKay shoes. It will be understood that in the manufacture of other classes of shoes an appropriate relating of the free margin of the upper to the surface of the sole to which it is to be secured may or may not be performed as a distinct step separate from the securing operation and the manner of securing the upper to the sole will be appropriately varied according to the class of shoes being manufactured without departing from my invention.

15 Figure 1 illustrates one way of practising this invention with the aid of formed wipers and pincers for stretching and wiping a shoe upper up and around the end of a last and illustrates the step of applying a binder for holding the tensioned upper against the surface of the last;

Fig. 2 is a perspective view illustrating the work produced by the operations indicated in Fig. 1;

20 Fig. 3 illustrates how the method of this invention may be extended to include steps of overlaying and securing the upper appropriately in the manufacture of a McKay shoe.

25 Fig. 4 is a perspective view of a McKay shoe produced by the operations shown in Figs. 1 and 3; and

30 Fig. 5 is a perspective view of one form of binder which may be used in practising this invention.

In boot and shoemaking, the upper is prepared and assembled upon a last together with a sole in proper position thereon for lasting. The first step in the process of toe 40 lasting is to stretch, wipe, or otherwise manipulate the upper to cause it smoothly and evenly to conform to the contour of the outer surface of the end of the last. As shown in the drawing pincers, one of which is 45 shown conventionally at 2, are used for seizing the edge or margin of the upper A and stretching the upper, and wiper plates, indicated at 1, are employed to embrace the end of the shoe and wipe or form the shoe upper 50 up around and firmly against the outside faces or surface B' of the last B and, if desired, substantially to the plane of the tread face of the sole C.

55 The pincer and the wiper mechanisms indicated in the drawings, which may be of well-known construction and arrangement, although I prefer to employ novel mechanisms fully described in my co-pending machine application Serial No. 635,183, upon 60 which Letters Patent No. 1,274,589 were granted on August 6, 1918, form no part of this present invention and are shown here merely as examples of means for manipulating an upper into conformity with the contour of the last around the toe below the edge

of the last bottom. While I prefer to employ wipers to gather the tensioned upper smoothly to the last edge, that is not necessary because it is known that an upper can be gathered at the toe by a cord or binder 70 without the aid of wipers.

When the upper has been satisfactorily stretched by the pincers, or stretched and shaped to the last, a flexible binder is applied around the toe in clamping engagement 75 with the upper exteriorly of the periphery of the shoe bottom or of the last and sole edge in accordance with this invention, and the binder is secured in position to hold the upper substantially at the edge of the last. A 80 binder which I have used with success is indicated at D in the drawings and comprises a ribbon or strip having a laterally bent flange D' at each end provided with holes to receive anchor tacks E, Fig. 2, said strip and 85 flanges being shaped relatively for the strip to embrace the side face of an inverted lasted shoe below the plane of the shoe bottom and for the flanges to extend inwardly over the shoe bottom for attachment of the binder 90 in holding relation to the toe of the shoe. This binder forms the subject-matter of a co-pending application Serial No. 766,472, upon which Letters Patent No. 1,306,121 were granted on June 10, 1919, and is not claimed 95 herein, being shown merely as one example of means adapted to be applied after the upper has been tensioned for clamping it exteriorly of the shoe bottom against slipping back when the edge of the upper is released. 100

The binder can be applied to the shoe manually by anchoring one end and then pulling upon the other end until the upper is securely clamped and thereafter inserting an anchor tack in the second end. I prefer, 105 however, to employ novel mechanism which I have designed for use for this purpose in connection with the pincer and wiper mechanism and which I have claimed in a co-pending application Serial No. 776,927, upon 110 which Letters Patent No. 1,036,120 were granted on June 10, 1919.

After the tensioned upper has been clamped, as by application of binder D, the devices 1 and 2, used in manipulating the 115 upper into conformity to the contour of the toe of the last, may be withdrawn from the lasted toe, leaving the margin of the upper upstanding and free above the plane of the sole.

120 The shoe as shown in Fig. 2 is now ready to be subjected to an upper and sole connecting operation appropriate for the class of shoes being made and if in that class of shoes the margin of the upper requires to be 125 formed down upon the tread face of the sole that step may be performed in conjunction with the connecting operation or prior thereto as desired. The binder D molds the upper to the last at the edge of the shoe and 130

also serves during an upper and sole connecting operation to prevent the edge rest of the connecting machine, such as a tacker or a sewer, from pushing the upper ahead and 5 producing a fullness at one side of the toe as the connecting operation progresses around the toe. The binder, moreover, constitutes a smooth firm surface with which the edge rest makes engagement so that a uniform location of an inseam around the toe can be 10 secured.

The shoe shown in Fig. 2 may be transferred to any desired location for the appropriate upper and sole connecting operation such as tacking, sewing, or cementing, according to the class of shoe being 15 manufactured. In Fig. 3 I have illustrated the usual upper and sole connecting operation for a McKay shoe, effected by a reciprocating wiper 3 and a tack driver 4 operating through a nozzle 5 and organized, for example, as fully set forth in my prior 20 United States Letters Patent No. 881,441, granted March 10, 1908. This or any other 25 upper and sole connecting operation suitable for the class of shoes being made may, however, be performed by hand or with the aid of any suitable tacking or sewing mechanism.

30 After the upper has been appropriately connected to the sole the binder D may be removed from the shoe by pulling out the tacks E and the binder may then be used again.

35 In the manufacture of McKay shoes the laying of the margin of the upper over the sole from the position shown in Fig. 2 to the position shown in Figs. 3 and 4 may be considered a part of the lasting operation 40 which is separated, in accordance with this invention, from the shaping of the upper to the contour of the last as shown in Figs. 1 and 2. The tacking operation may be performed by a less skilled operative than is 45 advantageously employed for the earlier operation, thereby effecting a saving in labor cost. In the manufacture of certain classes of shoes it is contemplated that under some 50 conditions the shoe having its forepart lasted in accordance with this invention as in Fig. 2 may be transferred directly to a welt-upper-and-sole sewing machine.

Having explained the nature of this invention and described how it may be practised, I claim as new and desire to secure by 55 Letters Patent of the United States:—

1. The improvement in the art of making boots and shoes which consists in stretching and forming an upper to the upper shaping 60 surface of the end portion only of a last, forming a flexible binder along its length into contact with the formed portion of the upper at the end portion only of the last along the edge thereof adjacent to the bot-

tom portion, and then securing the binder 65 in position to hold the end portion of the upper in conformity to the last.

2. The process of toe lasting which consists in stretching and forming an upper around and against the toe of a last by engaging the edge portion of the upper, applying a binder to the upper along the edge 70 of the last around the toe portion only thereof while the upper is held and securing the binder in place, then releasing the edge of 75 the upper, and subsequently forming the edge of the upper down upon the last by an inward wiping movement over the binder and last.

3. The process of toe lasting which consists in wiping an upper over the toe portion of a last and simultaneously stretching the upper by engaging its edge portion above the sole portion of the last, placing a binder in firm contact with the upper along the 80 edge of the shoe below the plane of the shoe bottom and securing the binder at the sides 85 of the toe portion of the shoe while the upper is being held stretched, and then forming the upstanding edge of the upper inward and down upon the bottom face of the sole by an inward wiping movement over the upper edge of the binder.

4. That improvement in methods of making shoes which consists in forming an upper to the contour of the toe of a last, then applying a binder of flexible material 90 tightly about the toe exteriorly of the periphery of the shoe bottom to hold the upper, laying the margin of the upper inwardly over the bottom of the last and fastening it while the upper is held by the binder, and thereafter removing the binder.

5. The process of toe lasting which consists in stretching an upper around and 95 against the toe of a last by engaging the marginal portion of the upper, applying a binder to the upper along the lateral periphery of the last around the toe portion 100 while the upper is held and securing the binder in place; and then releasing the margin of the upper and securing the upper to the shoe sole while it is held exteriorly of the shoe bottom by the binder.

6. That improvement in methods of making shoes which consists in conforming an upper to the contour of the toe of a last, temporarily securing the toe portion of the upper in its conformed relation to the last 115 by applying a binder of flexible material 120 about the toe exteriorly of the periphery of the shoe bottom and securing the binder, fastening the upper to the shoe sole while the upper is held by the binder, and thereafter removing the binder.

7. That improvement in methods of making shoes which consists in assembling an upper and a sole on a last, working the up-

- per into substantial conformity with the contour of the last around the toe below the edge of the last bottom, and holding the upper by its edge while applying a binder 5 around the toe exteriorly of the last and sole edge and securing the binder in position to hold the upper substantially at the edge of the last bottom when the edge of the upper is released.
- 10 8. That improvement in methods of making shoes which consists in assembling an upper and a sole on a last, engaging the marginal edge of the upper and stretching the upper into substantial conformity with 15 the contour of the last around the toe below the edge of the last bottom, gathering the tension upper smoothly to the last bottom substantially at the edge of the last and applying a flexible binder around the toe in position to clamp the tensioned upper on the lateral periphery of the last against slipping back, releasing the marginal edge of the upper, and subsequently securing the upper permanently to a sole and then removing the flexible binder.
- 15 9. That improvement in methods of making shoes which consists in engaging the marginal edge of an upper and stretching the upper into substantial conformity with 20 the contour of a contained last or form around the toe below the edge of the last bottom, gathering the tensioned upper smoothly to the edge of the last bottom and holding the upper against slipping back by 25 a flexible binder applied around the lateral periphery of the last, and then releasing the marginal edge of the upper and subsequently securing the upper permanently to a sole and removing the flexible binder.
- 30 10. That improvement in methods of making shoes which consists in conforming an upper to the contour of the toe of a last, applying a flexible binder about the toe exteriorly of the periphery of the shoe bottom 35 to hold the upper and inserting fastenings at opposite sides of the shoe to secure the binder in place, fastening the upper to the

shoe sole while the upper is held by the binder, and thereafter removing the binder.

11. That improvement in methods of making shoes which consists in assembling an upper on a last, manipulating the upper substantially into conformity with the contour of the last around the toe below the bottom of the shoe, and then so applying a binder around the toe below the plane of the bottom of the shoe as to hold the upper in conformity to the last and leave the margin of the upper at and above the last bottom free for manipulation in a subsequent upper and sole connecting operation.

12. That improvement in methods of making shoes which consists in assembling an upper on a last, and manipulating the upper into conformity with the contour of the last around the toe below the bottom of the shoe and applying to the toe below the plane of the tread face of the sole a thin flexible ribbon binder in position to present a guiding surface for engagement by a machine edge rest during a subsequent upper and sole connecting operation and hold the upper from being pushed ahead longitudinally of the shoe edge by the edge rest.

13. That improvement in methods of making shoes which consists in assembling an upper and an insole on a last, stretching the upper into conformity with the contour of the last about the toe of the last, temporarily securing said upper in stretched position by 75 applying a piece of flexible binding material tightly around the toe exteriorly of the periphery of the shoe bottom and securing said binding material at the sides of the shoe, securing the upper directly to the insole 80 by securing means extraneous of the binding material, and thereafter removing the binding material.

In testimony whereof I affix my signature in presence of two witnesses.

Certificate of Correction.

It is hereby certified that in Letters Patent No. 1,412,892, granted April 18, 1922, upon the application of Charles F. Pym, of Detroit, Michigan, for an improvement in "Processes of Lasting Boots or Shoes," errors appear in the printed specification requiring correction as follows: Page 4, line 17, claim 8, for the word "tension" read *tensioned*; same line, strike out the word "bottom" and insert the same to follow the word "last" in line 18; and that the said Letters Patent should be read with these corrections therein that the same may conform to the record of the case in the Patent Office.

Signed and sealed this 10th day of October, A. D., 1922.

[SEAL.]

WM. A. KINNAN,

Assistant Commissioner of Patents.
